UNITED STATES PATENT OFFICE,

WILLIAM GUTENKUNST, OF MILWAUKEE, WISCONSIN.

CORN-SEPARATING DEVICE FOR CORN-HUSKERS.

SPECIFICATION forming part of Letters Patent No. 738,321, dated September 8, 1903.

Application filed January 23, 1902. Serial No. 90,873. (No model.)

To all whom it may concern:

Be it known that I, WILLIAM GUTENKUNST, a citizen of the United States, residing at Milwaukee, county of Milwaukee, and State of Wisconsin, have invented new and useful Improvements in Corn-Separating Devices for Corn-Huskers, of which the following is a specification.

My invention pertains more especially to the combination and arrangement, with the discharge - duct which communicates from the corn husker and shredder to the fan-inclosing case, of a so-called "vacuum-chamber," through which air is drawn from the exterior by the action of the stalk-elevating fan, whereby the dust is separated from the shelled corn as it falls from the screen in said duct in its passage through said vacuum-chamber; second, to the device for elevating the shelled corn and discharging it into a receptacle therefor after the dust has been separated therefrom.

The construction of my invention is explained by reference to the accompanying drawings, in which—

Figure 1 represents a side view partly in section, and Fig. 2 is a front view thereof.

A represents the discharge end of an ordinary corn husker and shredder.

30 B is a fan, and C the fan-inclosing case, by which the shredded stalks passing through the machine are elevated.

D is the discharge-duct of the fan-inclosing case.

35 Interposed between the rear end of the machine proper and the fan-case C is a screen-inclosing case E, through which the shredded stalks are drawn from the machine by so-called "vacuum-pressure" produced by the 40 fan B, whereby the shredded stalks are drawn into the case C and discharged therefrom, as stated.

For the purposes of my present invention the screen employed for separating the shelled 45 corn from the shredded stalks may be either reciprocating, revoluble, or of any other desired construction which may best subserve the purpose intended. The lower side of the inclosing case E is provided with a partial 50 vacuum-chamber F, through which the corn

which is screened from the stalks is permitted to pass when it falls upon the downwardly-inclined ducts G and H and from thence is discharged into the transverse duct I.

It will of course be understood that as the fan B is operated a partial vacuum is formed within the screen-inclosing case E and chamber F, whereby a strong current of air is led from the exterior into said case and chamber 60 through the passage J beneath the screen, whereby the dust and other refuse matter escaping from the screens above are drawn by said current of air up into the fan-case C and discharged therefrom with the shredded 65 stalks. Thus it is obvious by this construction that I am enabled to utilize the same fan for separating the dust from the shelled corn that is used for elevating the stalks, whereby a separate fan heretofore employed for such 70 purpose is avoided.

K is an elevator into the lower end of which the shelled corn is led through said duct I, when it is elevated by the series of buckets L L to the top of the elevator and discharged 75 therefrom through the spout M into a sack or other receptacle provided therefor. The series of buckets L L are supported in the ordinary manner from an endless belt N, which belt is in turn supported at its respective 80 ends by ordinary pulleys O, one of which is shown at the lower end of said elevator. Motion is communicated to said elevator from a moving part of the husker and shredder through the belt P, pulley Q, and shaft 85 R, whereby as said machine is operated the shelled corn, which has been incidentally loosened from the ears during the process of husking, is not only screened out and separated from the stalks, but the dust and other 90 foreign matter that escape through the screen are entirely removed therefrom by the current of air which is drawn into the screen-case, while the corn which has been thus separated and cleaned is simultaneously elevated and discharged into sacks or other receptacles therefor.

Having thus described my invention, what I claim as new, and desire to secure by Letters Patent, is—

55

75

80

90

95

100

The combination with the fan and the discharge-duct through which the stalks are led to the fan of a vacuum-chamber located beneath and connected with the lower side of 5 said duct, and a screen located within said duct, substantially as and for the purpose described.

In testimony whereof I affix my signature in the presence of two witnesses.

WILLIAM GUTENKUNST.
